UNITED STATES PATENT OFFICE.

CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH-TUBE APPARATUS.

No. 880,595.

Specification of Letters Patent.

Patented March 3, 1908

Application filed July 28, 1906. Serial No. 328,197.

To all whom it may concern:

Be it known that I, CHARLES F. STODDARD, of Boston, in the county of Suffolk and State of Massachusetts, have invented certain new and useful Improvements in Pneumatic-Despatch-Tube Apparatus, of which the following is a specification.

My invention relates to the arrangement of pneumatic tube systems whereby the moisture of condensation is eliminated.

The figure shown in the drawing represents a system of two lines of pneumatic tubes, both radiating from the same station, the moisture being taken out of the air 15 pumped into one of the lines by means of receivers which act as surface condensers, and out of the other one by means of using the return air from the first line which is dried.

A and A' are compressors driven by the 20 motors B and B' respectively.

C and C' are transmitters and D and D' are receiving terminals.

E and E' are reservoirs.

The blowers A and A', motors B and B', 25 transmitters C and C', receiving terminals D and D' and reservoirs E and E' are all located at one station. Radiating from this station which is marked F are two lines of pneumatic tubes terminating at the stations 30 G G'. The air which propels the carriers in these two lines of pneumatic tubes is all compressed at the central station F. The route of the air from the compressor A is through the pipe H and the reservoirs E and E' are 35 located in a cool place so that the moisture in the air will be precipitated and settle to the bottom of the tanks where it can be drawn off at any time. From the reservoirs E and E' the air flows through the pipe H' and the 40 transmitter C and from thence to the pneumatic tube J and the receiving terminal D' at the station G. From here it is conducted along the pipe H² into the transmitter C² and into the pneumatic tube J² which returns to 45 station F entering the receiving terminal D where it has reached practically atmospheric pressure. From the receiving terminal D the air passes through the pipe H³ back to the compressor A where it is again compressed and sent over the same route. On 50 account of leaks in the pipes and pneumatic tubes, also on account of the lines at the receiving terminals D and D² and the transmitters C and C², also on account of the air taken away at the point H⁶ by the pipe H⁷

(the function of which will be explained later) not as much air returns to the compressor through the pipe H³ as was delivered from the compressor A to the pipe H, and this loss has to be made up at all times and 60 the compressor A supplied with as much free air as it delivers to the pipe H. In order to supply this deficiency, a pipe H⁴ is run from the compressor A to some suitable location H⁵ so that the compressor A may draw 65 in free air from this source.

The compressor A' supplies compressed air to the pneumatic tube line running to station G' through the pipe H⁸, and this compressed air flows into the transmitter C' from 70 the pipe H⁸, and thence to the pneumatic tube J³ to the station G' where it passes through the receiving terminals D³ and into the pipe H⁹ to the transmitter C³, returning to station F through the pneumatic tube J⁴, 75 entering the receiving terminal D' at practically atmospheric pressure and returning to the compressor A' through the pipes H¹ and H¹¹. As previously explained as to the line running to station G, there is considerable 80 loss of air due to leakages and also at the receiving terminals D' and D³ and transmitters C' and C³, so that the amount of air returning to the compressor A' through pipe H¹¹ is somewhat less than the amount delivered to the pipe H⁸. The deficiency in this case is made up from the pipe H⁷. The only source from which the pipe H⁷ can take air is the pipe H³, and as all the air in the pipe H³ 85 has passed through the reservoirs E and E' and through the pneumatic tubes J and J², it has become thoroughly dried, therefore all the air supplied to the pneumatic tube line running from station F to station G' has been thoroughly dried before it enters the compressor A' and for this reason there will be no 90 condensation of moisture in the pneumatic tubes J³ and J⁴.

As before explained, all the air which passes into the pneumatic tubes J and J² 100 flows through the reservoirs E and E' so that it is thoroughly dried. This arrangement makes it possible to supply dry air to any number of pneumatic tube lines with the use of but one reservoir outfit. Any number of 105 pneumatic tube lines radiating from the central station F could draw their supply of air necessary to make up their deficiencies from the pipe H³.

It sometimes happens when the ground is 110

very cold and the temperature of the outside air relatively high, that the outside atmosphere is very humid, and the reservoir outfit in such cases is unable to precipitate all the moisture in the air. It is found very desirable to concentrate this precipitation of moisture to one pneumatic tube line and by the arrangement shown this is made possible, for after the air has passed through one pneumatic tube line, it always returns to atmospheric pressure thoroughly dried. It is understood here that the term "dry air" does not mean an absolute absence of moisture, but that the amount of moisture contained in the air is so small that when the air enters the pneumatic tube from the compressor, and is cooled by the great surface of contact and material offered by the walls of the tube, no precipitation of moisture will result therefrom.

Having thus described the nature of my invention and set forth a construction embodying the same what I claim as new and desire to secure by Letters Patent of the United States is:

1. In a pneumatic despatch tube apparatus, a series of pneumatic despatch tube lines, a series of blowers for said tube lines, an atmospheric connection to the blower of the first pneumatic tube line, and a connection between said first pneumatic tube line and the blower of the second pneumatic tube line for supplying air current to said pneumatic tube line and closed to the atmosphere.
2. In a pneumatic despatch tube appa-

ratus, a series of pneumatic despatch tube lines, a series of blowers for said tube lines, an atmospheric connection to the blower of the first pneumatic tube line, means for drying the air in said first line, and a connection between said first pneumatic tube line and the blower of the second pneumatic tube line for supplying air current to said pneumatic tube line and closed to the atmosphere.

3. In a pneumatic despatch tube apparatus, a series of pneumatic despatch tube lines, a blower open on one side to the outside atmosphere and communicating at the other side with the transmitting terminal of the first tube line, a tank interposed in the communication between the blower and the first tube line, a pipe connecting the receiving terminal of the first tube line with the open side of the blower, a second blower communicating at one side with the transmitting terminal of the second tube line, and a closed communication leading to the other side of said second blower from the pipe connecting the receiving terminal of the first tube line with the first blower and said closed communication also leading from the receiving terminal of the second tube line.

In testimony whereof I have signed my name to this specification, in the presence of two subscribing witnesses, this twenty first day of July, A. D. 1906.

CHARLES F. STODDARD.
